W. E. MEADWELL,
MEASURING INSTRUMENT,
APPLICATION FILED DEC. 18, 1915.

1,239,502.

Patented Sept. 11, 1917.

UNITED STATES PATENT OFFICE.

WILLIAM E. MEADWELL, OF ITHACA, NEW YORK, ASSIGNOR OF ONE-THIRD TO JOHN O. LITTLE, OF PITTSBURGH, PENNSYLVANIA.

MEASURING INSTRUMENT.

1,239,502.

Specification of Letters Patent. Patented Sept. 11, 1917.

Application filed December 18, 1915. Serial No. 67,630.

To all whom it may concern:

Be it known that I, WILLIAM E. MEADWELL, citizen of the United States, residing at Ithaca, in the county of Tompkins and State of New York, have invented certain new and useful Improvements in Measuring Instruments, of which the following is a specification.

My invention relates to measuring instruments and more particularly to a proportional photo-engraving measuring scale.

The primary object of my invention resides in the provision of a scale for measuring photographs, engravings and the like to enable advertisers, catalogue recorders, printers, publishers, etc., to show the other dimension of a cut made from an odd size photograph or drawing when either the horizontal or vertical dimension can be named off-hand. While it is not always necessary for practicable purposes to know both dimensions of the cut ordered, it is desirable in many cases where space in an advertisement, catalogue or other literature is limited and it is desired to set up the type matter in advance of the receipt of the cut and in such cases by the use of my novel scale, the party ordering the cuts can advise his printer the exact size of both sides of the cuts to be sent, enabling the printer to set the type more carefully without feeling that leads may have to be added or removed to care for either larger or smaller cuts than expected.

Another object of my invention resides in the provision of a pair of relatively movable arms and a sliding arm associated with one of the arms, which arm is incidentally normally stationary for coöperation with the other arm.

Another object of this invention resides in the provision of the novel means for connecting the relatively movable arms so as to facilitate the maintenance of the said arms in their adjusted position as well as novel means for removably mounting and holding the sliding arm in position the sliding arm being removable at times to permit of the device to be arranged in a compact manner and thereby occupying a minimum amount of space when not in use.

Another object of this invention resides in the provision of a scale of the type described which can be used for solving simple problems in proportion referring to anything in mathematics so that the said problems can be solved incidentally and read direct from the scale without chance or error as with the ordinary sliding rule now in use, and dividing them for instance into 1000 equal parts or divisions.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claims forming a part of this specification.

In the drawings:

Figure 1 is a top plan view of my invention;

Fig. 2 is a transverse sectional view of the sliding arm showing to advantage the manner in which it is associated with the normally stationary arm as well as the means for maintaining these arms in substantially rigid yet movable relation; and

Fig. 3 is a transverse sectional view taken on line 3—3 of Fig. 1 in the direction in which the arrow points.

Referring more particularly to the drawings in which similar reference numerals designate like and corresponding parts throughout the several views, I provide a pair of complementary relatively movable arms 1 and 2, the arm 1 being provided with a plurality of graduations and being normally stationary when in use.

It is to be understood that these arms may be formed of any desirable material and they are preferably relatively flat in cross section.

A disk like extension 3 is formed integral with and projects from one corner of the arm 2 and is provided with an opening 4. Another disk like extension 5, similar to the 100

extension 3, projects from the arm 1 and is also provided with an opening. A metallic rivet 6 is passed through the openings in the extensions and has the respective ends 5 terminating in flanges 7 which are arranged in close relation to the outer sides of the extensions and frictionally engaging the latter to consequently facilitate the maintenance of the arms 1 and 2 in adjusted positions. It 10 is to be understood, as clearly shown in the drawings that the apex of the angle formed by the arms 1 and 2 lies in the opening formed by the hollow rivet 6, the hollow rivet therefore providing a sight opening for 15 facilitating accurate measurements to be calculated, as will be presently apparent.

Associated with the arm 1 is a sliding arm 3. This arm is formed of a similar material and of the same construction as the arms 1 20 and 2, although the inner end is enlarged into a rectangular formation as illustrated by the numeral 8. This enlarged portion is bent upon itself as illustrated by the numeral 9 while a free terminal is off-set as 25 illustrated by the numeral 10 and rigidly connected to itself through the medium of rivets or other fastening device 11. By this arrangement it will be observed that an opening 12 is provided, the walls of which 30 are adapted to be arranged in close relation with the outer surface of the arm 1. In order to removably hold the arm 3 in various adjusted positions on the arm 1 I have provided a set screw 13 and removably adjustably mounted the same in a threaded opening 14 in the enlargement 8, the inner end of the screw frictionally engaging the arm 1. The arm 3 is also provided with a plurality of graduations which extend from 35 the inner side of the arm 1 as illustrated to advantage in Fig. 1 of the drawings. This peculiar manner of associating the arm 3 with the arm 1 permits of the efficient adjustment on the arm 1 as desired.

40 In use, assuming that it is desired to measure a photograph to consequently obtain a desired half-tone, the scale is placed upon the photograph so that the connecting point between the arms 1 and 2 is arranged, for instance, at and over the left hand corner of the horizontal base line of a photograph, said corner being observed through the sight opening provided by the hollow rivet 6 so that the apex of the angle formed by the 45 arms 1 and 2 will be coincident with said corner of the photograph or object to be measured. The arm 1 is now arranged along the left vertical side of a photograph and the arm 2 is placed perfectly over the corner 50 diagonally opposite to the connecting point of the arms 1 and 2. It is not necessary to know the dimensions of the photograph or drawing. If a cut of for instance 4 inches vertical is needed, the arm 3 is moved up or 55 down the arm 1 to the 4 inch mark and the 60

arm 2 extends out for coöperation with the arm 3 to consequently indicate the horizontal dimensions of the cut. Fig. 1 in the drawings does not show a photograph but it will be noted that the cut would be 2 and 70 $\frac{5}{8}$ inches vertically and would be 2 inches horizontally.

Although I have shown and described the preferred embodiment of my invention I desire it to be understood that I am not to be 75 limited to the exact details shown; however, I desire great stress to be laid upon the arrangement of the relatively movable arms, one of which is stationary and a sliding arm for coöperating with the relatively movable 80 arm for accomplishing the purpose set forth. Attention is also directed to the peculiar arrangement of the arm 3 with the arm 1.

From the above description taken in connection with the accompanying drawings, it 85 can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general embodiment of my invention and that various minor changes in 95 detail of construction, proportion and arrangement of the parts may be made within the scope of the appended claims and without sacrificing any of the advantages of my invention.

Having thus fully described my invention, what I claim as new and desire to secure by Letters Patent, is:—

1. A measuring instrument of the class described comprising two similar arms each 105 having a straight edge, a lateral projection extending from each arm and having an opening therein in alinement with the straight edge of the arm, a tubular rivet adapted to extend through the openings in 110 said projections for pivotally connecting the arms together and for providing a sight opening for the instrument, another arm having one end bent upon itself to form a loop, one of said first mentioned arms being 115 adapted to slidably extend through said loop, and thumb screw threaded in said loop portion for securing the sliding arm in adjusted positions.

2. As a new article of manufacture, an 120 advertiser's device for proportionally measuring photographs, advertisements, and the like, comprising two similar arms each having a straight edge and an opening therein, a tubular rivet extending through the openings in said arms for pivotally connecting them together and for providing a sight opening, the opening in each arm being arranged in alinement with the straight edge thereof so that the apex of the angle formed 130

by the straight edges will lie at the center of the sight opening, and another arm for removable and slidable engagement with one of said first mentioned arms and to extend substantially perpendicularly thereto for coöperation with the other of said first mentioned arms.

In testimony whereof I affix my signature in presence of two witnesses.

WILLIAM E. MEADWELL.
